CLAIM

The ornamental design for a refrigerating diaper receptacle, as shown and described.

DESCRIPTION

FIG. 1 is a perspective view of a refrigerating diaper receptacle according to the present invention.

FIG. 2 is a front side view of the refrigerating diaper receptacle according to the present invention.

FIG. 3 is a right side view of the refrigerating diaper receptacle according to the present invention.

FIG. 4 is a left side view of the refrigerating diaper receptacle according to the present invention.

FIG. 5 is a top side view of the refrigerating diaper receptacle according to the present invention.

FIG. 6 is a bottom side view of the refrigerating diaper receptacle according to the present invention; and,

FIG. 7 is a back side view of the refrigerating diaper receptacle according to the present invention.

The broken lines as shown for the vents in FIGS. 3 & 4, and the features shown in FIGS. 6 & 7 represent environment and form no parts of the claimed design.
